JOHN F. O'CONNOR, OF CHICAGO, ILLINOIS, ASSIGNOR TO WILLIAM H. MINER, OF CHAZY,
NEW YORK.

FRICITION-PLATE DRAFT-GEAR WITH ANTIFRICITION WEDGING MEMBERS.

1,300,463.

Specification of Letters Patent.

Patented Apr. 15, 1919.

Application filed May 21, 1917. Serial No. 170,023.

To all whom it may concern:

Be it known that I, JOHN F. O'CONNOR, a citizen of the United States, residing at Chicago, in the county of Cook and State of Illinois, have invented a certain new and useful Improvement in Friction-Plate Draft-Gears, with Antifriction Wedging Members, of which the following is a full, clear, concise, and exact description, reference being had to the accompanying drawings, forming a part of this specification.

My invention relates to improvements in friction plate draft rigging for railway cars.

The object of my invention is to provide an efficient draft rigging.

In the drawings forming a part of this specification, Figure 1 is a horizontal section of a draft rigging embodying my invention; Fig. 2 is a cross section taken on line 2-2 of Fig. 1; Fig. 3 is a perspective view of one of the stationary plates; and Fig. 4 is an enlarged internal view of one side of the front portion of the shell.

Referring to the drawings, the numerals 25 10-10 indicate center sills or draft members, being the parts of the car underframe to which the draft rigging is applied. The front stop members are shown at 11-11, and the rear stop members at 12-12. The draft

30 gear 13 is mounted between the draft members and is supported in its position by the tie-plate 14 which is removably secured to the draft members, as, for instance, by the bolts 15-15. By means of a yoke 16 the draft gear 13 is connected to the draw-bar.

35 A front follower 18 is, together with the draft gear, mounted within the yoke. The draft gear 13 comprises a shell 19 open at its front end and closed at its rear end by the preferably integral plate 20 which serves as a rear follower. Within the shell are the spring elements 120 and the friction elements 21. The friction elements comprise the sets of friction plates 21 and 22 arranged at either side of the shell at its forward end. Each set of friction plates comprises the alternately arranged stationary plates 24 and

40 the movable plates 25. The stationary plates 24 are provided at their upper and lower ends with the protruding portions or lugs 26 which are adapted to enter the recesses 27-27 provided in the upper and lower portions, respectively, of the shell to prevent the longitudinal movement of the said plates while permitting a lateral movement therein.

The movable plates are seated at their rear ends against an internal follower 28 which in the normal position of the parts of the gear, as shown in Fig. 1 of the drawings, is spaced away from the rear edges of the 60 stationary plates. Interposed between the two sets of friction plates is a spreading device 29 which engages the front follower 18 at one end and the internal follower 28 at the other. The said spreading device 65 consists of a pair of oppositely arranged L-shaped members having substantially parallel outer faces 30 and the opposed internal wedging faces 31-31, there being preferably a plurality, as, for instance, two of these, as 70 shown in the drawing, with the anti-friction rollers 32 interposed.

In normal position of the parts, a space is provided between the front ends of the movable friction plates, as indicated at the numeral 33 in Fig. 1 of the drawings, so that on rearward movement of the draw-bar the front follower moves rearwardly, driving the spreading member rearwardly against the resistance of the springs 120 which are 80 seated between the internal follower 28 and the rear member 20 of the shell until the front follower 18 engages the front ends of the movable friction plates. The friction plates are pressed into engagement with 85 each other by the spreading member, and the movable plates as they are forced rearwardly by the front follower resist the front follower through their frictional engagement between the movable plates. 90

On forward movement of the draw-bar, the shell is drawn forwardly by the yoke, the springs exert pressure against the internal follower 28, and the said follower forces the movable plates forwardly and spreads 95 the spreading device 29 between it and the front follower 18, thus creating friction between the movable and the immovable plates and resisting the forward movement of the shell in a manner that will be readily understood. 100

I claim:

In a friction shock absorbing mechanism, the combination with a shell; of a plurality of friction plates mounted within said shell 105 and immovable longitudinally thereof; of a plurality of friction plates alternated with respect to said immovable friction plates and adapted to slide between said immovable plates; spring means within said shell and 110

2
adapted to resist relative movement between said movable friction plates and the shell; and wedging means associated with said friction plates, said wedging means comprising two opposed members having outer substantially parallel faces and provided on their inner opposed faces with duplicate sets of wedge surfaces, and a pair of anti-friction rollers interposed between said wedge

surfaces, said wedging means being located 10 centrally of the friction plates with substantially one-half of the latter on each side thereof.

In witness that I claim the foregoing I have hereunto subscribed my name this 30th 15 day of April, 1917.

JOHN F. O'CONNOR.
